UNITED STATES PATENT OFFICE

2,084,066

METALWORKING PRESS

Fredrich J. Rode, Chicago, Ill., and Adam Ziska, Wauwatosa, Wis., assignors, by direct and mesne assignments, of one-third to said Rode, one-third to Rudolph W. Glasner, Chicago, Ill., and one-third to Clearing Machine Corporation, Chicago, Ill., a corporation of Illinois

Application April 28, 1933, Serial No. 668,318

4 Claims. (Cl. 113—38)

This invention relates to improvements in metal working presses, and one of the objects of the same is to provide a press of this character which will be of a steel welded construction, that is the front and back walls of the press will be formed from plates, and these parts together with the end walls or uprights will be secured together by welding, with the result that the cost of manufacture and of assembling will be greatly reduced, and a compact arrangement will be produced.

Important economies can be effected as the different parts can be cut and welded to the proper size, eliminating the necessity of patterns and their well known inelasticity for changes. Another important advantage is the added strength obtainable, coupled with greatly reduced weight of material used in the making of the press. The elimination of many parts which formerly made up a press of this character, such as for instance the bed, crown, uprights, tie rods, etc., results in great saving of labor and in the machining and assembly, and further assures greater accuracy in the finished machine.

A further object is to provide improved means for reciprocating the ram whereby the crank shafts which are usually arranged parallel with the front and rear faces of the press will be dispensed with, and the ram will be actuated by mechanism which is housed within the press and arranged so that all of the stress and strain of the ram as well as the actuating mechanism, will not only be borne by the front and rear plates of the press, but all of the stresses and strains exerted by the work will be within the confines of the frame structure. The end walls or uprights serve only to resist any tendency of the front and rear walls becoming displaced with respect to each other under such strains.

A further object is to provide improved actuating mechanism for the ram, which embodies bull gears having eccentrics directly attached thereto, the axes of the eccentrics and of the gears being arranged transverse to the front and rear walls of the press, the gears and eccentrics being supported entirely by the front and rear plates or walls, connections being made between the eccentrics and the ram at four points, preferably adjacent the corners of the ram, to maintain the ram against tilting movement, at any time during the operation of the press.

To the attainment of these ends and the accomplishment of other new and useful objects as will appear, the invention consists in the features of novelty in substantially the construction, com-

bination and arrangement of the several parts hereinafter more fully described and claimed and shown in the accompanying drawings illustrating this invention and in which

Figure 1 is a view partly in front elevation, partly in section and partly broken away, and with parts omitted, of a press of this character constructed in accordance with the principles of this invention.

Figure 2 is an irregular vertical sectional view taken on line 2—2, Figure 1.

Figure 3 is a top plan view, on an enlarged scale, of Figure 1, and with parts omitted.

Figure 4 is a horizontal sectional view, on an enlarged scale, taken on line 4—4, Figure 1, and with parts omitted.

Figure 5 is a vertical sectional view, on an enlarged scale, taken on line 5—5, Figure 3.

Figure 6 is a horizontal sectional view, on an enlarged scale, taken on line 6—6, Figure 1, and with parts omitted.

Referring more particularly to the drawings, the numerals 10 and 11 designate respectively the front and rear members of the press, and these members are formed of steel plates of the desired configuration, provided with the necessary openings which serve as bearings for the parts to be hereinafter described, and to facilitate access to the work and to other parts of the mechanism, such openings being arranged wherever desired or necessary.

The end walls 12 are also formed preferably of steel plates and the front, rear and end walls are secured together by brazing or welding so as to form an entire steel welded structure, the end walls being of suitable length to provide the necessary space between the front and rear walls or plates and in which space the ram actuating mechanism is arranged.

A portion of the front plate may be provided with supports 13 arranged in a position to support a bed or bolster plate 14 also secured in position by being welded, brazed, or otherwise permanently fastened to the supports 13.

In presses of this character the bed or bolster plate 14 supports a usual die 15 having a work holding ring or member 16 co-operating therewith, the latter being supported by the usual pins 17 which pass loosely through the bed or bolster plate 14, and rest upon a pad 18 usually supported by means of a cushioning device 19 arranged below the bed or bolster plate.

The numeral 20 designates a reciprocable ram movable upon guides 21 supported by the portions 22 of the front and rear plates and which por-

tions constitute the uprights of the press, and the ram 20 may be counterbalanced by means of counterbalancing devices 23, any number of which may be provided and preferably of the pneumatic cylinder type, the devices embodying piston rods 24 connected to pistons within the cylinders 23 (not shown) and also connected by means of arms or brackets 25 with the ram 20.

The operating mechanism for the ram which 10 will effect a reciprocation of the ram, is arranged within the space between the front and rear walls or plates, and embodies bull gears 26 mounted upon shafts 27, which latter have bearings in the front and rear walls or plates 10 and 11 of the press, and the shafts 27 are so arranged that the axes thereof and of the gears 26 are arranged transverse to the front and rear walls or plates 10 and 11 and parallel with the end walls or uprights 12.

20 The gears 26 are preferably arranged in alignment with each other and out of mesh, and secured to each of the gears 26 to rotate therewith and on each side of the respective gears are eccentricities 28, the gears and the respective eccentricities being preferably of an integral formation.

Eccentric straps 29 encompass the respective eccentricities 28 and connected to each of the eccentric straps 29 are links 30 which in turn are 30 connected to the ram 20.

Four of the eccentricities and the eccentric connections with the ram 20 are preferably provided and the connections with the ram are preferably made at the corners thereof to form what might 35 be termed a "four point suspension" for the ram, and these connections operate not only to reciprocate the ram but to maintain the ram against a tilting movement at any time during the cycle of operation of the press or reciprocation of the 40 ram.

By reason of the fact that the axes of the gears 26 and eccentricities 28 are transverse to the front and rear walls or plates of the press, and as the eccentricities are connected directly with the respective gears 26, it will be manifest that a very compact arrangement may be provided and the usual 45 crank shafts for reciprocating the ram and which extend in directions parallel with the front and rear faces of the press, will be dispensed with.

50 Motion is imparted to the gears 26 preferably by means of a motor 31, preferably mounted upon a bracket 32. Connected with the shaft of the motor is a pulley 33, over which a belt 34 passes, and this belt also passes over a pulley 35 connected to a shaft 36, which latter is journaled in the front and rear walls or plates 10 and 11 of the press, the axis thereof being parallel with the axes of the gears 26.

Connected with the shaft 36 to rotate therewith 60 are gears 37, preferably two in number, which in turn mesh with gears 38 secured to a shaft 39 for rotation therewith, and this shaft 39 is journaled in suitable bearings 40 in the front and rear walls or plates 10 and 11 of the press 65 and are housed therebetween.

One of the gears 38 meshes with another gear 41 also housed within the press and this gear 41 is connected to a shaft 42 for rotation therewith, and the shaft 42 is journaled in suitable 70 bearings 43 in the front and rear walls or plates 10 and 11. The shafts 39 and 42 project through and beyond the front wall or plate 10 a sufficient distance to have respectively secured thereto and for rotation therewith gears 44-45. The gears 75 44 and 45 respectively mesh with gears 46-47

arranged preferably on the outside of the plate or wall 10 and secured respectively to shafts 48-49 for rotation therewith. These shafts 48-49 are journaled respectively in suitable bearings 50-51 in the front and rear walls or 5 plates 10 and 11.

Secured respectively to the shafts 50-51 and for rotation therewith are gears 52-53 which in turn mesh respectively with gears 26, and to which latter the respective eccentricities are secured for rotation so that by the operation of the motor the main driving shaft 36 will be rotated and motion will be imparted from this shaft through the medium of the gear 31 to the gear 38. The gear 38 meshing with the gear 41 will rotate the latter and also meshing with the gear 52 will rotate it, while the gear 41 meshing with the gear 53 will rotate the latter.

The rotation of the gears 52 and 53 and meshing respectively with the gears 26 will rotate them and this in turn will rotate the respective eccentricities 28 to cause a reciprocatory movement to be imparted to the ram 20, and upon which ram 20 the usual die 54 that co-operates with the die 15, is mounted.

With this improved construction it will be manifest that a very compact arrangement of press will be provided and that the cost of manufacture and of assembling the press will be greatly reduced. At the same time the usual long crank shafts which extend parallel with the front and rear faces of the press will be obviated, and in the present construction none of the welds will take any direct strain of the working parts, but all of the stress and strain of the operation upon the work will be borne entirely by the front and rear plates or walls of the press and all objectionable torque will be overcome. The end walls 12 serve only as a means for maintaining the front and rear walls against displacement with respect to each other and for the purpose of maintaining a rigid structure.

Obviously the end walls may be of any desired thickness and suitable portions of the end walls may be hollow for the sake of lightness.

It will also be obvious that webs or braces 55 may be provided between the front and rear walls or plates, if desired or necessary, and suitably arranged, and the front and rear walls may, if desired, be fastened together by suitable tie rods or bolts 56.

It is also obvious that the structure may be reinforced or braced wherever necessary or desired, and the press may be supported upon any suitable form or type of base. The press is preferably supported by means of braces 57 which may engage and rest upon a suitable support 58, such as the floor of a building, and an opening or pit 59 may be provided, if necessary, so as to receive the lower extremity of the press and the cushioning device 19, if the latter is employed.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A supporting frame for power presses or the like, formed by front and rear upright plates, spaced upright columns formed integral with and depending from each of the plates, said columns on each plate being in alignment but spaced from each other, end walls arranged ad-

5 jacent the longitudinal edges of the uprights and at the ends of the plates above the uprights, the edges of the plates being welded together, and integral bed supporting portions carried by
 10 5 and disposed between the uprights, the said uprights at the ends of the bed being uninterrupted, the upper portions of the plates constituting a hollow crown, there being aligned shaft bearing openings in the front and rear plates of the 10 crown portion of the press, within the confines of and spaced from the edges of said plates, and within the confines of the said upright columns.
 15 2. A supporting frame for power presses or the like, formed by solid and comparatively thin front and rear upright plates, spaced upright columns integral with and depending from each of the plates, end walls arranged adjacent the longitudinal edges of the uprights and at the ends of the plates above the uprights, the edges 20 20 of the plates being welded together, and bed supporting portions integral with and disposed between the uprights, the said plates constituting a hollow crown, in combination with shafts having bearings directly in the plates within the 25 25 confines of and spaced from the edges of the front and rear plates and extending across the faces therebetween, said shafts being also disposed within the confines of said upright columns, whereby all vertical stresses of said shafts 30 30 will be sustained by and exerted in directions edgewise of said plates, and driving gears of substantial diameter carried by the shafts and dis-

posed within the hollow crown, and located directly above the press slide.

3. A power press embodying a bed, spaced uprights, a crown, a slide reciprocably mounted between said uprights and said bed and crown, 5 said crown embodying front and rear plates comparatively thin with relation to their other dimensions, means for connecting said plates together, a shaft mounted in said plates and extending from front to rear of the press, said shaft 10 being located within the confines of said uprights and also spaced from the edges of the plates, whereby the vertical stresses exerted by said shaft are absorbed by said plates in a direction edgewise of said plates, and eccentric means be- 15 tween said shaft and slide.

4. A power press embodying a bed, spaced uprights, a crown, a slide reciprocably mounted between said uprights and said bed and crown, said crown embodying front and rear plates comparatively thin with relation to their other dimensions, means for connecting said plates together, two shafts mounted in said plates and extending from the front to the rear of the press, both of 20 20 said shafts being located within the confines of 25 said uprights and also spaced from the edges of the plates, whereby the vertical stresses exerted by said shafts are absorbed by said plates in a direction edgewise of said plates, and eccentric means individual to and between each of said 30 30 shafts and said slide.

FREDRICH J. RODE.
ADAM ZISKA.
